UNITED STATES PATENT OFFICE.

JOHN E. SWANSON, OF CENTERVILLE, SOUTH DAKOTA.

SAFETY-ENVELOP.

1,124,358.

Specification of Letters Patent.

Patented Jan. 12, 1915.

Application filed April 12, 1913. Serial No. 760,787.

To all whom it may concern:

Be it known that I, JOHN E. SWANSON, a citizen of the United States, residing at Centerville, in the county of Turner and 5 State of South Dakota, have invented certain new and useful Improvements in Safety-Envelops; and I do hereby declare the following to be a full, clear, and exact description of the invention, such as will 10 enable others skilled in the art to which it appertains to make and use the same.

This invention relates to new and useful improvements in safety envelops.

As its principal object, this invention 15 tempts the provision of means for sealing and attaching the correspondence interiorly of the envelop and exteriorly holding the closure flaps in the inclosed relation.

The above and additional objects are 20 accomplished by such means as are illustrated in the accompanying drawings, described in the following specification and then more particularly pointed out in the claims which are appended hereto and form a part of this 25 application.

With reference to the drawings, wherein I have illustrated the preferred embodiment 30 of my invention as it is reduced to practice, and throughout the several views of which similar reference numerals designate corresponding parts: Figure 1 is a plan view of the blank from which the envelop is constructed. Fig. 2 is a plan view illustrating the end flap in folded position; and Fig. 3 35 is a plan view illustrating the complete folded position of the various flaps of the envelop.

Proceeding now to the description of the drawings, the blank from which the envelop 40 is constructed includes a main body portion 1 substantially rectangular in shape, but which may be made in any desired shape and of any required dimensions.

Extending from the end edge 2 of the 45 member 1 is a semicircular flap 3 provided with a locking tongue 4, adapted to be inserted, as at 5 in Fig. 2, in the lateral slit formed in the end flap 6, carried on the end edge 7 of the member 1. The flap 6 is provided on its longitudinal edges with the

sealing flaps 8 and 9, which may be gummed for the obvious purpose of holding the correspondence in place on the inner face of the flap 6. The longitudinal edges of the member 1 carry the side flaps 10 and 11 55 which are preferably tapered outwardly and carry at their outer terminals laterally extending locking tongues 12 and 13, the member 12 being arranged on one side of the lateral center line of the member 1 and the member 13 being arranged on the other side. The members 12 and 13 each terminate adjacent the center line above referred to in locking tongues 14 and 15, formed by slitting the members 11 and 10 on the lines 60 16 and 17, as at 18 and 19.

In use, the correspondence is placed on the flap 6, the gummed members 8 and 9 are moistened and are folded to engage the letter or other correspondence. The flap 6 is 70 then folded inwardly on the edge 7 to bring the correspondence within the flap 6 and the body portion 1. The flap 3 is then folded on the line 2 and the tongue 4 is inserted in the lateral slit 5 of the flap 6. It then remains to fold the members 10 and 11 on the 75 longitudinal edges of the blank and to lock the tongues 14 and 15 by merging the slits 18 and 19 as illustrated in Fig. 3.

In reduction to practice, I have found 80 that the form of my invention, illustrated in the drawings and referred to in the above description, as the preferred embodiment, is the most efficient and practical; yet realizing that the conditions concurrent with the 85 adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:

The herein-described safety envelop comprising a body portion, a foldable flap integrally connected to one edge of said body portion, said flap having foldable and gummed margins to inclose the correspondence, and said body portion adapted to be folded over said flap, top and bottom fold- 95 100

able sealing flaps extending from the upper and lower edges of the body portion, said sealing flap having oppositely disposed tongues, said tongues each having oppositely disposed slits parallel with the sides of the body portion when folded, said slits adapted to be interlocked, and a flap extending from the side edge of the body por-

tion and provided with a tongue to engage a slit in the first mentioned flap. 10

In testimony whereof I affix my signature in presence of two witnesses.

JOHN E. SWANSON.
